MAIL BOX SUPPORT

Filed Dec. 1, 1922

FIG. 2.

FIG. I.

FIG. 3.

Inventor:
Hans Strehberg

UNITED STATES PATENT OFFICE.

HANS SKREBERG, OF BIG BEND TOWNSHIP, MINNESOTA.

MAIL-BOX SUPPORT.

Application filed December 1, 1922. Serial No. 604,386.

To all whom it may concern:

Be it known that I, HANS SKREBERG, a citizen of the United States, and a resident of Big Ben Township, in the county of Chippewa and State of Minnesota, whose post-office address is Milan, Minnesota, have invented a new and useful Improvement in Mail-Box Supports, of which the following is a specification, reference being had thereto in the accompanying drawings.

My invention relates to improvements in mail box supports.

The object of my present invention is to provide a simple, neat and efficient means whereby rural mail boxes in particular can be properly secured to any suitable post.

It is a well known fact that rural mail boxes should be placed conveniently along the routes served by carriers. Further it is readily understood that placing the box on top of or close to the post requires that carrier drive close to post in order to reach the mail box.

I provide a bracket that makes mail box hang out away from post and further I provide a bracket that will swing to right or left and return to its normal position.

A preferred and practical embodiment of the invention is shown in the accompanying drawings, in which:

Figure 1 is a side elevation of my improved mail box support.

Figure 2 is a top plan view of the construction shown in Figure 1.

Figure 3 is a side elevation of a modification.

Figure 4 is a detail cross sectional view taken on the line 4-4 of Figure 2.

Similar reference characters designate corresponding parts throughout the several figures of the drawing.

In carrying the present invention into effect, it is proposed to provide an improvement in the general type of mail box support shown in my former Patent No. 928,075, dated July 13, 1909. In the present case, however, it is proposed to provide an attaching bracket A and a box carrier B which are pivotally connected in the manner of a hinge, the pintle C of the hinge being maintained in inclined position whereby the box carrier will tend to return to its normal position by gravity. Heretofore, it has been the practice for the box support or carrier to remain in a deflected position, but according to the present construction,

the box will always return to its normal straight out position.

The attaching bracket A may be secured in any suitable manner to the post 1 which may be of wood, steel or the like, and the body of the box carrier B preferably consists of the angular arm members 2 and 3, the short arms of which are preferably arranged in a vertical position and held together by means of the oppositely disposed U-shaped clamps 7 and 8 which include the compression bolts 9 and 10. The said oppositely disposed U-shaped clamps respectively engage opposite sides of the inclined rod 6 which constitutes the pintle member C previously referred to, and according to the illustration in Figure 1 the opposite ends of the said pivot rod 6 engage in the upper and lower eye members 4 and 5 respectively of the attaching bracket A. It will also be observed from Figure 1 that the lower U-shaped clamp 8 rests upon the lower eye 5 of the attaching bracket.

Adjacent the angle in the arms 2 and 3, at the upper side thereof, there is provided an eye member 13 which is adapted to engage over the upper end of the rod 6 which projects above the eye 4. This eye member 13 may be secured to the arms by means of the fastening 14.

The forwardly extending horizontal portions of the arms 2 and 3 may be secured together in any suitable manner, and as shown more plainly in Figure 2 the outer ends thereof may be bent in opposite directions to permit of the angle iron 16 being secured thereto, thereby providing a transverse support for the platform or shelf member 15 on which the mail box rests. Also the rear end of the platform 17 may be further secured to the horizontal portion of the arms 2 and 3 through the medium of the bolts 17.

It will, of course, be understood that the mail box or other receptacle may be suitably secured in any well known manner to the platform 15 which affords an adequate point of support therefor.

A modification of the invention is shown in Figure 3 of the drawings, wherein the attaching bracket A' and the pintle member C' are made in one piece, while the box carrier B' may retain the same structural features and characteristics as shown in Figure 1. In this form of embodiment the attaching bracket A' may be provided with

the post attaching bolt portions 21 which are continuations of the horizontal portions of the member which forms the inclined pivot rod 6^a which constitutes the pintle C' 5 previously referred to.

In the construction of Figure 1 the clamp 8 is preferably rigidly clamped to the rod 6 so as to furnish a support for the same on the lower eye 5. However, if desired the 10 upper end of the rod 6 may be provided with a cotter pin 18 as shown to safeguard against looseness of the clamp.

From the foregoing, it will be apparent that in either form of my invention I provide 15 an inclined pintle which functions to permit the box carrier to seek its normal position.

Without further description it is thought that the features and advantages of the invention will be readily apparent to those 20 skilled in the art, and it will, of course, be understood that changes in the form, pro-

portion and minor details of construction may be resorted to, without departing from the spirit of the invention and scope of the 25 appended claim.

I claim:

A receptacle support of the class described, including a post, a bracket carried by the post and having an inclined pintle member, 30 a box carrier mounted on said inclined pintle, said box carrier comprising angle bars having the ends of their horizontal arm portions turned outwardly, an angle member secured to the out-turned ends of said angle bars, a platform secured to the angle member and angle bars, and means carried by the vertical arms of said angle bars for engaging the inclined pintle. 35

HANS SKREBERG.
